COMBINED STAND AND HOLDER FOR A
BABY FOOD JAR

Edward G. Mueller, 1102 W.O.W. Bldg., Omaha, Nebr.

Filed July 16, 1963, Ser. No. 75,835

Term of patent 7 years

(Cl. D83—8)

FIG. 1.

FIG. 4.

FIG. 2.

FIG. 3.

FIG. 5.

FIG. 1 is a top plan view of a combined stand and holder for a baby food jar showing my new design;

FIG. 2 is a side elevational view thereof;

FIG. 3 is a front elevational view;

FIG. 4 is a front perspective view in the direction 4—4 of FIG. 2; and

FIG. 5 is a fragmentary rear elevational view as seen in the direction 5—5 of FIG. 2.

I claim:

The ornamental design for a combined stand and holder for a baby food jar, substantially as shown.
